UNITED STATES PATENT OFFICE.

ALDEN D. BLAKE, OF DETROIT, MICHIGAN.

AUXILIARY AIR DEVICE.

1,364,176.

Specification of Letters Patent. Patented Jan. 4, 1921.

Application filed April 6, 1918. Serial No. 227,097.

To all whom it may concern:

Be it known that I, ALDEN D. BLAKE, a citizen of the United States of America, residing at Detroit, in the county of Wayne 5 and State of Michigan, have invented certain new and useful Improvements in Auxiliary Air Devices, of which the following is a specification, reference being had therein to the accompanying drawings.

10 This invention relates to auxiliary air devices and refers more particularly to a new and improved construction whereby an auxiliary amount of either hot or cold air can be supplied to the manifold of an internal 15 combustion engine.

Among the objects of the invention are to provide a control mechanism or valve which in one position of adjustment will 20 connect the valve cylinder to a supply of hot air and in another position of adjustment open it to a source of cold air; to provide a construction which can be economically manufactured and conveniently attached to standard constructions of automobiles; to provide means for adding a predetermined amount of moisture to the auxiliary 25 supply of air; to utilize the auxiliary air device for priming purposes and as a lock; and in general to provide an improved 30 and simplified construction of the character above referred to.

The invention also resides in the particular valve arrangement and in such further features of construction and arrangements 35 and combinations of parts as will more fully hereinafter appear.

In the drawings:

Figure 1 is a diagrammatic elevational view showing a device embodying my invention installed in connection with an automobile engine;

Fig. 2 is an enlarged vertical sectional view through the control valve;

Fig. 3 is a horizontal section on the line 45 3—3 of Fig. 2;

Fig. 4 is an enlarged vertical section through the cold air inlet opening of the casing;

Fig. 5 is an enlarged sectional view on the 50 line 5—5 of Fig. 1.

Describing in detail the particular embodiment of my invention illustrated and referring first to the general construction shown in Fig. 1, A designates an internal 55 combustion engine having an inlet manifold B receiving the explosive mixture from the

carbureter C. D designates the exhaust manifold through which the hot exhaust gases are discharged through the pipe E. In running internal combustion engines, 60 particularly those of automobiles, it is found that greater efficiency can be obtained by supplying an additional amount of air to the carbureter mixture under certain working conditions of the engine. For this purpose I have provided an auxiliary air device comprising a valve casing F, the ports of which are controlled by a valve G. The operating stem G' for rotating the valve is adjusted by a lever H which can be extended 70 to any convenient position for operation, 75 preferably to a position on the dash or steering post.

The valve casing F is provided with a port J which is connected by a pipe J' to 75 the inlet manifold of the engine preferably above the carbureter. Another port K is open to the air for receiving a supply of air at atmospheric temperatures while a third port L is connected by a pipe L' to 80 an air inlet opening under the hot-plate L² which is fastened over the exhaust manifold L³. Each of the ports are controlled by the valve G which, as shown in Figs. 2 and 3, is formed in the shape of a cylinder 85 sleeved within the casing F and provided with ports M, M' and M² which control the passage of air into the cylinder and also control the amount passing through the auxiliary air device to the manifold. The ports 90 M and M² are preferably of a size to register with the manifold port J and the cold air port K so that a relatively large supply of cold air can be secured. Upon turning the valve to the left a quarter of a turn 95 the port M² will register with the hot air port L and the port M' will register with the inlet manifold port J. It will be noticed that the port M' is formed in the shape of a triangle so as to differentially increase the amount of opening to the manifold port J when an auxiliary supply of 100 heated air is added to the carbureter mixture.

In place of using air having an atmospheric humidity I preferably employ the construction wherein a hollow wire O has one end arranged to open in the upper part of the engine radiator header Q while the other end of the hollow wire extends beneath the hot-plate L² so that when the valve is adjusted to supply heated air to 105 110

the carburetor mixture it will supply air which contains a greater degree of moisture than usual.

In order to permit of a standard size and construction being employed with cars having a capacity for taking a greater or lesser amount of auxiliary air supply, there is provided in the branch connection R leading from the hot air port L a cylindrical member S having a port S' which restricts the hot air opening to a greater or less degree. By supplying these auxiliary cylinders which have ports of various diameters, it is possible to employ one size of valve 15 casing for engines having different capacities. In such case it is only necessary for the installer to select the cylinder having the proper port opening or he can stamp out or form in the end of the cylinder an opening of the desired size.

In order to permit the auxiliary air casting F being employed for priming purposes the cold air inlet K has a lip or cup construction K' formed on its outer surface so 25 as to receive a small amount of priming fluid. I also utilize the auxiliary air device as a lock for preventing theft of the car.

As shown in Fig. 4 the valve G has at 30 its upper end a lug G² which is provided with an opening G³ registering with a corresponding opening F³ in a lug F² on the casing F. This registration of the openings G³ and F³ takes place when the valve 35 G is adjusted to the position where the ports M and M² are in full registration with the ports K and J, as illustrated in Fig. 3. It has been found in practice that when

these ports are in full registration it will be totally impossible to start the car owing 40 to the excess amount of cold air which is furnished to the intake manifold. By simply inserting the hasp V' of the padlock V through the openings G³ and F³ a simple and efficient locking arrangement is ob- 45 tained.

Various changes, however, in the details of construction can be made without departing from the scope of my invention.

What I claim as my invention is:— 50

1. An auxiliary air device for internal combustion engines, comprising a casing having an inlet for cold air, an inlet for heated air and a connection with the intake manifold of the engine, and a cylindrical 55 valve adapted in different positions of rotative adjustment to connect said cold air inlet and said heated air inlet to said intake manifold, said valve and casing being provided with means for locking the valve with 60 the cold air inlet open to the intake manifold of the engine.

2. An auxiliary air device for internal combustion engines, comprising a casing having an inlet for cold air and a connection with the intake manifold of the engine, a cylindrical valve having ports adapted in one position of adjustment to connect the cold air inlet to the intake manifold, said valve and casing having coöperating 70 lugs registering when the cold air inlet is fully open, and means engaging said lugs for locking said air inlet opening in its open position.

In testimony whereof I affix my signature. 75
ALDEN D. BLAKE.
